CLAIM

I claim the ornamental design for a lighting device, as shown and described.

DESCRIPTION

FIG. 1 is a perspective view of a lighting device in an expanded configuration showing my new design, as viewed from the top and one side.

FIG. 2 is a front elevation view of the lighting device of FIG. 1 in the expanded configuration.

FIG. 3 is a first side elevation view of the lighting device of FIG. 1 in the expanded configuration.

FIG. 4 is a second side elevation view of the lighting device of FIG. 1 in the expanded configuration.

FIG. 5 is a back elevation view of the lighting device of FIG. 1 in the expanded configuration.

FIG. 6 is a top plan view of the lighting device of FIG. 1 in the expanded configuration.

FIG. 7 is a bottom plan view of the lighting device of FIG. 1 in the expanded configuration.

FIG. 8 is a perspective view of the lighting device of FIG. 1 in a collapsed configuration, as viewed from the top and one side; and,

FIG. 9 is a perspective view of the lighting device of FIG. 1 in the collapsed configuration and with extended mounting clips, as viewed from the bottom and one side thereof.

The details shown in broken lines illustrate portions of the lighting device that form no part of the claimed design.

1 Claim, 6 Drawing Sheets
